UNITED STATES PATENT OFFICE.

HENRY Z. COBB, OF WINCHESTER, MASSACHUSETTS.

BRAIDING-MACHINE.

1,117,330.

Specification of Letters Patent. Patented Nov. 17, 1914.

Application filed October 18, 1911. Serial No. 655,352.

To all whom it may concern:

Be it known that I, HENRY Z. COBB, a citizen of the United States, residing in Winchester, in the county of Middlesex and 5 State of Massachusetts, have invented certain new and useful Improvements in Braiding-Machines, of which the following is a specification.

This invention relates to machines for the 10 production of braided fabrics, and particularly tubular fabrics adaptable for use as hose. In the making of two-ply or multiple-ply braided fabrics, it is desirable to unite the braided webs by some textile connection other than that afforded by the webs 15 themselves, in order that each web may be distinct. In my Patent No. 937,021 granted October 12, 1909, I have set forth a means for uniting distinct parallel braided webs 20 by interlacing with them uniting strands interbraided with the respective webs by means of a supplemental series of bobbins, which in a braiding machine pass alternately between the raceways traversed by 25 the bobbins which braid the respective webs. The product of that invention is a tubular fabric of two (or more) plies, each ply constituting a distinct braided web, and these being intimately united by strands or yarns 30 interbraided with each, and passing alternately from each into the other, these interbraiding or connecting yarns traversing the tubular fabric completely so as to constitute a series of helices; and being preferentially extended in right and left spirals so as 35 to cross and interbraid with each other.

My present invention produces a fabric in which the interconnecting yarns or strands instead of progressing helically 40 around the tubular fabric, are extended longitudinally thereof and are interwoven with the braided yarns. The product is therefore somewhat similar to what might be produced by sewing single threads through it 45 from its outer to its inner sides, such threads forming parallel lines of stitching uniting the outer and inner webs at sufficiently frequent intervals.

The invention finds its greatest utility in 50 the case of two-ply or multiple-ply hose; but it is applicable to a single-ply hose in which the longitudinal strands or webs have the effect not only of strengthening the fabric but of directly resisting a longitudinal 55 pull thereon, and consequently rendering it

less liable to stretch than is an ordinary braided hose.

In practising my invention I may employ an ordinary braiding machine, preferably one capable of simultaneously braiding two or more webs, and I combine with this machine a means for introducing the desired number of longitudinal warp yarns into the braided fabric, such means consisting preferably of shuttles with suitable mechanism for throwing them in proper succession through the shed of converging yarns from the braider bobbins. The braided fabric being delivered longitudinally without rotary or twisting motion, and the shuttles 60 being each confined to its own path, these paths being fixed or non-rotative, it follows that the yarns paid off from these shuttles and interwoven with the braided yarns, constitute true warps, since they extend longitudinally of the fabric, as distinguished from those which progress spirally or helically around the tubular fabric, as in the case of my previous patent.

In the accompanying drawings,—Figure 80 1 is a vertical mid-section showing one embodiment of this invention as applied to an ordinary type of multiple-ply braiding machine; Fig. 2 is a partial horizontal section of the machine taken mainly in the plane 85 of the line 2—2 in Fig. 1, and showing the relative arrangement of the bobbin raceways and the warp shuttles; Fig. 3 is a fragmentary plan partly in horizontal section showing the gearing for driving the respective 90 shuttle throwing mechanisms; Fig. 4 is a vertical section on a larger scale showing one of the shuttle throwing mechanisms and the shuttle in its relation thereto; Figs. 5 and 6 are respectively side and front elevations 95 of one of the shuttles; Fig. 7 is a plan thereof showing also its raceway, and Fig. 8 is an enlarged sectional view showing a detail; Figs. 9 and 10 are respectively an elevation and a longitudinal section of the produced 100 fabric.

Referring to the drawings, A designates the core on which the braiding is done, and B the bobbins which are carried by carriers C C which traverse sinuous race-ways 105 D D (Fig. 2) in a well known manner. The race-ways are cut in the usual plates F beneath which is the usual plate G, and between these plates are the usual gears (not shown) which drive the bobbin carriers, all 110

these parts being well understood in broiding machines.

A in Fig. 1 is the usual driving shaft from which motion is taken for driving the 5 various parts of the broiding machine. In the present machine this shaft through miter gears and an intervening shaft I drives an upper shaft J; and it also drives an upright shaft K. From these shafts J 10 and K the shuttle operating mechanism to be described is driven.

The yarns *a a* which are drawn off from the bobbin carriers, converge at the broiding point *b* where they are drawn together upon 15 the core A to form the broided fabric A'. A take-up is provided for moving the finished fabric up out of the machine as fast as it is produced, whereby to keep the broiding point *b* at the same place. The converging 20 yarns *a a* constitute a shed which is in the form of an obtuse cone. In the case of a two-ply fabric this shed is in fact double, the yarns forming one ply interlacing and drawing together distinctly from those 25 which form the other ply or web.

As many shuttles are provided as the number of warps to be introduced into the fabric. Six for example are shown in Fig. 2. Each of the shuttles L is carried on a 30 slide or other suitable carrier M, and this in turn is adapted for engagement with the shuttle guides or raceways P P. These latter are arranged partly above and partly below the shed of converging yarns *a*, or in other words are made in two alined sections 35 separated by a sufficient space to enable the converging yarns of the shed to pass freely between them. This space or gap is bridged by the shuttle slide or carrier M in moving 40 across the gap. Each shuttle moves at prescribed intervals from one side to the other of the shed, their respective positions being shown in Fig. 1 in full lines and in dotted lines. Thus the warp yarn *c* which is paid 45 off from the shuttle is moved alternately above and beneath the shed, so that it passes back and forth from the outside to the inside of the finished product. The shuttle is pointed at both ends so as to readily separate 50 the broiding yarns *a a* in passing through the shed.

The shuttles may be driven across the shed at the prescribed intervals by any one of a variety of shuttle throwing mechanisms. 55 The requisite of such mechanisms is that they shall move their respective shuttles quickly enough so that the passage of the shuttle through the shed shall not interfere with the desirably free movement of the converging broiding yarns. It is also desirable that the shuttle throwing mechanism shall move the shuttles in a prescribed succession and at prescribed intervals of time, in order to pass the warps through the fabric 60 with the desired frequency and in the

desired relation. As this is partly a matter of taste or caprice according to the appearance desired to be produced, no specific proportioning of the moving parts is essential to the invention.

The drawings show a suitable and the preferred shuttle throwing mechanism, but this is illustrated only as an instance of many different mechanisms that might be devised for this purpose.

This mechanism will now be described. The raceway P for each shuttle is formed partly in an upper frame Q and partly in a lower frame Q', there being of course as many pairs of these frames Q Q' as there 80 are shuttles. As they are duplicates of each other except for their relative inversion, a description of one will suffice. Taking the upper frames Q, each is formed at its lower end with the race-way P, which is here 85 shown as a dovetail groove fitting the dovetail sides of the shuttle slide or carrier M. In each frame Q is mounted a plunger R which moves in line with the shuttle carrier M, and which when it descends pushes down 90 the carrier M and thereby forces the shuttle to cross the shed into the race-way formed in the opposite frame beneath. The plunger R is suitably guided and is pressed upwardly by a spring S reacting against the frame Q, 95 and which is best coiled around a sliding rod S' as shown. For driving down the plunger R it is shown as provided with rack teeth d which are engaged by the teeth of a train of mutilated gears, as best shown in Fig. 4. 100 The rack is directly engaged by the teeth of a wheel e which is fixedly connected to a stop gear f which is driven by a mutilated gear g on a shaft h. The gear f has a concave which receives the toothless periphery 105 g' of the gear g, so that while this portion is in engagement with it, the wheel f is held stationary. At the prescribed time the teeth on the gear g engage the teeth of the gear f and turn it and the gear e through one revolution. The teeth of the gear e thereupon engage with the rack teeth d and push down the plunger R until the last tooth e' disengages itself from the rack teeth, so that the 110 plunger is set free, whereupon it is immediately returned to its original position by the expansion of the spring S. A buffer i is provided to relieve the shock at the instant of stopping the movement of the plunger. The gears g f e are driven at such speed that the described movement of the plunger occurs with such rapidity as to cause the shuttle to move as quickly as is desirable through the shed. Immediately upon the completion 120 of this movement, the plunger is released and quickly springs back to its former position, so that it offers no obstacle to the free movement of the yarns in the shed.

The construction of the parts related to the lower frame Q' is precisely the same ex- 125

cept for their being relatively inverted. The upper frame is provided with a yielding stop *j* to uphold the shuttle carrier after it is pushed up, and prevent its falling out of place; while this may be duplicated in the lower frame, yet this is not essential, as the weight of the shuttle and its carrier will keep them down in place. The stop *j* as shown is a spring bolt with a rounded end so shaped as to offer only sufficient resistance to the downward movement of the shuttle carrier to prevent its falling, but without seriously obstructing its being pushed down by the plunger.

15 The group of mutilated gears described with reference to Fig. 4, is duplicated for each one of the shuttles. This requires that motion be imparted continuously to the shafts *h* of each one of these series of mechanisms. A suitable and convenient connection for accomplishing this is that best shown in Fig. 3, where the shaft *h* already described is driven by miter gears *k* directly from the shaft *J*, and in turn the shaft *h* at its opposite ends is provided with miter gears which mesh with the next successive shafts *h'*, and these in turn with shafts *h''*, and so on, until the entire series of shafts has been completed, which with six shuttles requires the one additional shaft *h³* as shown. The bearings of these shafts and the various connected mechanisms are mounted upon a suitable supporting frame *R*.

35 The mechanism just described is duplicated for the upper series of plungers and for the lower series of plungers, with only this difference, namely, that the shafts of the lower series of mutilated gears take their motion from the upright shaft *K* through bevel gears *k'* as shown in Fig. 1.

40 The precise construction of the shuttle is not important. That shown in Figs. 5 to 8 has the bobbin or cup *l* mounted within a skeleton frame which on one side has a hinge member *m*, the free end of which is engaged by a spring latch *p* (Fig. 8) which may be released by an operating pin *q*.

45 The fabric which is produced by this machine is shown in elevation in Fig. 9, and in approximate vertical section in Fig. 10. In these figures *a* are the braided yarns and *c* are the longitudinal warp yarns which are laid in by the shuttles, the latter being shown as of darker color to more effectually distinguish them. In Fig. 10 the two braided plies or webs are distinguished by the layers *w* and *v*. The inner layer *w* is the usual rubber tube which forms the lining of the hose. This tube may itself constitute the core *A*

in Fig. 1, or this core may be any suitable 60 mandrel.

It will be observed that the warp yarns *c* by being repeatedly passed between the inner and outer surfaces of the fabric, not only serve to strongly unite the outer and inner 65 webs or plies, but also serve to impart longitudinal strength to the fabric by resisting a stretching strain. This resistance they afford however with a certain degree of elasticity due to the zigzag path which they 70 make in passing through the plies. The use of these longitudinal warps is also of advantage in a one-ply braided fabric, which is strengthened and made more resistant against stretching strains by the presence of 75 these warps.

The process and product herein described are not claimed in the present application, being made the subject of a divisional application filed April 8, 1912, No. 689,232. 80

I claim as my invention:—

1. A braiding machine combined with shuttles adapted to cross the shed of braiding yarns to introduce longitudinal warp 85 yarns, and mechanism for throwing the shuttles through the shed, such mechanism comprising a continuously moving driving part and mutilated gears.

2. A braiding machine adapted for making a tubular fabric, combined with a series 90 of shuttles adapted to cross the shed of braiding yarns to introduce longitudinal warp yarns, and mechanism for throwing the shuttles through the shed in succession, such mechanism comprising a continuously 95 moving driving part and mutilated gears.

3. A braiding machine combined with shuttles for introducing longitudinal warp 100 yarns and shuttle throwing mechanism comprising opposite plungers, and mutilated gears engaging the respective plungers at intervals to project them to push the shuttles through the shed.

4. A braiding machine combined with shuttles for introducing longitudinal warp 105 yarns and shuttle throwing mechanism comprising opposite plungers, and intermittently acting gearing adapted to engage and alternately project the opposite plungers to throw the shuttles through the shed. 110

In witness whereof, I have hereunto signed my name in the presence of two subscribing witnesses.

HENRY Z. COBB.
